United States Patent Office.

SOLOMON CROWELL, OF SYRACUSE, NEW YORK.

Letters Patent No. 87,148, dated February 23, 1869.

IMPROVEMENT IN PUMP-PISTONS.

The Schedule referred to in these Letters Patent and making part of the same.

To all whom it may concern:

Be it known that I, SOLOMON CROWELL, of Syracuse, in the county of Onondaga, and State of New York, have invented a new and useful Improvement in Pumps; and I do hereby declare that the following is a full, clear, and exact description thereof, which will enable those skilled in the art to make and use the same, reference being had to the accompanying drawings, forming part of this specification, in which the view shown is a vertical section of a pump having my improvement.

This invention relates to certain improvements in that class of pump-boxes, or valves, which are made of leather or other flexible material, and of a conical form.

The upper edges of such valves have heretofore been supported by straps of leather, but such straps soon stretch, or lengthen out, so as to let the body of the valve down, and the valve gets so out of shape that it is soon impaired or worn out.

These valves are used chiefly in sheet-metal canal-boat pumps, and they are used so irregularly that the valve is liable to be dried up, and much out of shape when wanted.

To obviate these objections, I support the upper edges of the valve by strips of spring-metal, so that the edges of said valve are free to move radially, but are not allowed to sag or settle down, and the valve thereby get out of shape. And also to make it keep its form to a greater degree when in disuse, or to not get out of shape by being dried up, I place a spring inside of the cone, as hereinafter more fully explained.

In the accompanying drawings—

A is the conical leather valve;

B is the pump-rod, or staff; and

C C are strips of spring-metal, for holding up the body of the valve.

D is a spiral spring, for holding the valve distended, and for making it retain its shape when dried up.

By the use of the spiral spring, a piece of flimsy leather can be made to answer the purpose of the best sole-leather.

The metallic strips, or bands C C, are riveted to the staff, and their lower ends secured to the edge of the valve, as usual, or they may be extended to the lower part of the valve, and there secured.

A flat spring, placed on the inside of the valve at its top, can be used in place of the spiral spring shown.

At least one end of the distending-spring D is left free to move around in direction of the coil.

This construction of valve is found to entirely overcome the objections which it is designed to obviate.

I am aware that a valve has been made in which the lower ends of the metallic supporting-straps are extended down to the lower end of point of the cone, and there secured to the rod; therefore I do not claim this.

Having thus described my invention,

What I claim as new, and desire to secure by Letters Patent, is—

The combination of the valve A, spiral spring D, supporting-straps C, and rod B, all as and for the purposes herein set forth.

The above specification of my invention signed by me, this 25th day of June, 1869.

SOLOMON CROWELL.
